UNITED STATES PATENT OFFICE.

KARL A. OLSON, OF PLAINFIELD, NEW JERSEY.

DIVING-BELL.

1,302,422.

Specification of Letters Patent. Patented Apr. 29, 1919.

Application filed April 23, 1918. Serial No. 230,221.

To all whom it may concern:

Be it known that I, KARL A. OLSON, a citizen of the United States, and residing at Plainfield, in the county of Union and State of New Jersey, have invented certain new and useful Improvements in Diving-Bells, of which the following is a specification, such as will enable those skilled in the art to which it appertains to make and use

10 the same.

This invention relates to diving bells for use in deep water in raising sunken ships, vessels and the like, and the object of the invention is to provide improved means for 15 supporting the tools used in apparatus of this class as well as the devices to be connected with such vessels; a further object of the invention being to provide an improvement of this character which is simple 20 in construction and operation and efficient in use.

The invention described and claimed herein is an improvement on that shown and described in U. S. patent to W. D. Sisson, No. 1,134,963 granted April 6, 1915, and is fully disclosed in the following specification, of which the accompanying drawings form a part, in which the separate 25 parts of my improvement are designated by 30 suitable reference characters in each of the views, and in which:

Figure 1 is a front view of a diving bell of the class specified with my improvement connected therewith;

Fig. 2 a partial section on the line 2—2 of Fig. 1 and on an enlarged scale and indicating the use of my improvement;

Fig. 3 a partial section on the line 3—3 of Fig. 2;

Fig. 4 a sectional side view similar to Fig. 2 but showing the tool and workpiece carrier without any of the tools or workpieces mounted therein, and indicating a rotary member in its inoperative position;

Fig. 5 a partial section on the line 5—5 of Fig. 4 but indicating one of the tools employed and the method of connecting it with the rotary member;

Figs. 6, 7 and 8 are detail views of the 50 tools and attaching devices employed; and,

Figs. 9, 10 and 11 show the method of connecting the attaching devices to the hull of a vessel.

In Figs. 1 to 5 inclusive, I have indicated 55 at 20 a part of the hull of a diving bell, such as shown in the patent above referred

to, and in Fig. 1 of the drawing a face view of the complete bell is indicated in dotted lines, and 21 indicates the magnets employed in apparatus of this class and 22 are 60 the observation lenses employed as in said patent.

In the practice of my invention, the hull 20 adjacent to the observation lenses 22 is provided with an enlarged bearing portion 65 23 through which passes the usual rotary member or shaft 24, which extends into the diving bell and is packed as shown at 25, and through which, in the practice of my invention, is passed a rod 26, the inner end 70 of which is packed as shown at 27 and provided with an angular end portion 28, whereby the same may be rotated by a suitable wrench or crank, and the outer end of which is threaded as shown at 29. The 75 above-named parts may be of the usual or any desired construction, and the end of the rotary member 24 is preferably provided with a conical or tapered aperture 30, the opposite side walls of which are provided 80 with key recesses 31 which extend the full length of said aperture, as clearly shown in Fig. 4.

The enlarged portion 23 of the hull is provided at one side of the rotary member 85 24 with an outwardly directed bearing 32 in which is rotatably mounted a shaft 33, the inner end portion of which is packed as shown at 34, and mounted on the inner end portion of said shaft and within the 90 diving bell is a nut 35 having an enlarged base flange 36 provided with a plurality of apertures 37 arranged in pairs as shown in Fig. 3, and a headed pin 38 is adapted to operate in connection with the apertures 95 37 in the flange 36, and an aperture 39 in the hull, or the enlarged portion 23 thereof. The inner end of the shaft 33 is made angular in form as shown at 40 whereby a wrench, crank or similar device may be 100 connected therewith for rotating the same.

The outer end of the shaft 33 protrudes beyond the bearings 32 and secured to the protruding end thereof is a tool and workpiece carrying member 41, comprising inner 105 and outer disks 42 and 43 connected centrally by a hub portion 44 riveted to said disks, and by rivets 45 as clearly shown in Figs. 1 and 2 of the drawing.

The inner and outer disks 42 and 43 are 110 provided with a plurality of corresponding apertures 46 which are in common aline-

ment, as clearly indicated in Figs. 1, 2 and 4, and these apertures are adapted to receive and support various tools and work-pieces, and in Fig. 6 of the drawing I have shown a drill 47 provided centrally with an enlarged flange or collar 48, and at its inner end with a tapered head 49 spaced from the collar 48 by a reduced neck 50, and the tapered head 49 is provided on opposite sides 5 with longitudinal flanges or keys 51 which are adapted to operate in connection with the key recesses 31 in the conical or tapered aperture 30, in the end of the rotary member, and the inner face of the head portion 10 49 is provided with a threaded aperture 52 adapted to receive the threaded end 29 of the rod 26 as clearly shown in Fig. 2 of the drawing.

I also employ a tap 53 having a central 20 enlarged flange or collar 54 and an inner tapered head member 55 provided with keys 56. The head member 55 is connected with the collar 54 by a reduced neck portion 57, and the inner end of the head member 55 is 25 provided with a threaded aperture 58 adapted to receive the threaded end 29 of the rod 26.

In Fig. 8 I have shown one of a number 30 of attaching devices 59, one end of which is threaded as shown at 60, and the other end provided with a tapered head member 61 provided with opposite side keys 62, and centrally thereof with an enlarged flange or collar 63 connected with the head member 35 61 by a reduced neck portion 64, and the end of the head member 61 is provided with a threaded aperture 65 adapted to receive a threaded end 29 of the rod 26.

In Fig. 1 of the drawing, I have shown 40 the tap 53 and five of the attaching devices 59 supported in the apertures 46 in the manner of the supporting of the drill 47, as shown in Fig. 5, in which position the reduced neck portion 50 of the drill is shown in engagement with the aperture 46 in the disk 42 and the enlarged flanged portion 48 supported between the inner and outer disks and this method of supporting the drill, tap and attaching devices prevents their 50 placement or disengagement from the carrying member 41, but in Fig. 1 of the drawing and as in Fig. 2 the drill 47 is shown in engagement with the rotary member 24 and supported centrally of the apertures 46, and 55 the method of attaching the drill, tap and attaching devices with the rotary member, as indicated in Fig. 2, is accomplished in the following manner.

In Fig. 5, as above stated, I have shown 60 the drill 47 in its normal position, or supported by the carrying member 41 which is the position of the tap and attaching devices shown in Fig. 1, and said tools and attaching devices are so supported that the 65 tapered heads thereof clear the outer end

portion of the rotary member 24, as clearly shown in Fig. 5, and when it is desired to drill a hole into the hull of a vessel as shown at 66 in Fig. 9, the carrying member 41 is rotated by turning the shaft 33, as above set out, to bring the drill 47 supported in the apertures 46 in the inner and outer disks of said member in line with the rotary member 24, after which the headed pin 38 is placed in position to lock said parts against movement, after which the rotary member 24 and rod 26 are moved outwardly and said rod rotated by means of a crank, as above set out, to secure the head member 49 of the drill in engagement with said rotary member, and this position of the parts is indicated in dotted lines in Fig. 5, and in accomplishing this result it will be noted that the drill 47 is held against outward movement by the engagement of the outer face of 85 the head portion 49 with the walls of the aperture 46 in the inner disk 42 as is evident on a consideration of Fig. 5 of the drawing. When the drill is connected, or secured to the end of the rotary member 24 90 as above set out, the headed pin 38 is removed and the carrying member 41 is rotated to a slight extent to bring the drill 47 centrally of the apertures 46 in the inner and outer disks 42 and 43, after which said pin is again placed in position to lock the parts against movement and the rotary 24 carrying the drill 47 is moved outwardly through the carrying member 41 as indicated in full and dotted lines in Fig. 2 of 100 the drawing, and the hole 66 is drilled in the hull. I have not shown the means for moving the rotary member 24 outwardly nor the means for rotating the same for the reason that my invention is not limited to 105 this feature, and it may be the same as the means employed in the patent above referred to, or as usually employed in apparatus of this class.

After the hole 66 has been drilled in the 110 above manner, the rotary member is moved inwardly and the above operation of attaching the drill therewith is reversed to again place said drill in the position shown in Fig. 5 of the drawing, after which the carrying member 41 is rotated to bring the tap 53 in position to be connected with the rotary member, and said tap is operated to thread the aperture 66 in the hull, as shown at 67 in Fig. 10, and afterward the tap is 115 replaced in the carrying member in the manner of replacing the drill, and the carrying member 41 is again manipulated to bring one of the attaching devices 59 into position to be connected with the rotary member 24, and said member is operated to secure 120 said device to the threaded aperture 67, as shown at 68 in Fig. 11 of the drawing.

Heretofore in order to accomplish the above described operations a drill is first 130

connected with the diving bell when above water and said bell is dropped or moved downwardly into the water and held in engagement with the vessel by the magnets 21 and a hole is drilled in the hull by said drill, and in order to tap said hole the diving bell must be raised to the surface, the drill removed and the tap substituted therefor, and in order to connect the attaching device with the threaded hole in the hull, the diving bell must be again raised and much time, labor and energy is lost in accomplishing the desired result, while with my improvement the diving bell may be held in engagement with the hull of a vessel in the desired position by the magnets 21, and when in such position a hole may be first drilled in the hull, and then said hole threaded and the attaching device connected with the threaded hole without moving the diving bell from such position, furthermore the diving bell may be moved around the hull by the usual propeller mechanism employed, which mechanism is not shown, and a plurality of attaching devices may be connected with the hull without raising said diving bell to the surface of the water, and with the construction shown in Fig. 1, five of these attaching devices may be connected with the hull, but it will be understood that the carrying member 41 may be so constructed as to support any number of attaching devices or tools of various kinds and classes, the chief feature of my invention being the provision of means for supporting tools and attaching devices and for bringing them into position to be engaged and supported by a rotary member operated from within the diving bell.

While I have shown and described certain details of construction for carrying my invention into effect, it will be understood that my invention is not limited to such details, and changes therein and modifications thereof may be made, within the scope of the appended claims, without departing from the spirit of my invention or sacrificing its advantages.

Having fully described my invention, what I claim as new and desire to secure by Letters Patent, is:—

1. In an apparatus of the class described, a hull, a rotary member mounted therein and movable inwardly and outwardly therethrough, and a carrying member rotatably mounted in the hull adjacent to said rotary member and adapted to support a plurality of tools and attaching devices.

2. In an apparatus of the class described, a hull, a rotary member mounted therein and movable inwardly and outwardly therethrough, a carrying member rotatably mounted in the hull adjacent to said rotary member and adapted to support a plurality of tools and attaching devices, and means for operating said carrying member to bring the

tools and attaching devices supported therein in line with said rotary member.

3. In an apparatus of the class described, a hull, a rotary member mounted therein and movable inwardly and outwardly therethrough, a carrying member rotatably mounted in the hull adjacent to said rotary member and adapted to support a plurality of tools and attaching devices, means for operating said carrying member to bring the tools and attaching devices supported therein in line with said rotary member, and means for connecting said tools and attaching devices with said rotary member.

4. An apparatus of the class described, comprising a hull, a rotary member mounted in said hull and movable inwardly and outwardly therethrough, a carrying member mounted in the hull adjacent to said rotary member, means within said hull whereby said carrying member may be rotated, and the carrying member being provided with means for supporting tools and attaching devices therein.

5. An apparatus of the class described, comprising a hull, a rotary member mounted in said hull and movable inwardly and outwardly therethrough, a carrying member mounted in the hull adjacent to said rotary member, means within said hull whereby said carrying member may be rotated, the carrying member being provided with means for supporting tools and attaching devices therein, and means for locking said carrying member in different positions of adjustment.

6. An apparatus of the class described, comprising a hull, a rotary member mounted in said hull and movable inwardly and outwardly therethrough, a carrying member mounted in the hull adjacent to said rotary member, means within said hull whereby said carrying member may be rotated, the carrying member being provided with means for supporting tools and attaching devices therein, means for locking said carrying member in different positions of adjustment, and means for securing said tools and attaching devices in connection with said rotary member.

7. An apparatus of the class described, comprising a hull, a rotary member mounted in said hull and movable inwardly and outwardly therethrough, a rod mounted in said rotary member, means within the hull whereby said rod may be rotated, a carrying member connected with the hull adjacent to said rotary member, the carrying member being provided with means for supporting tools and attaching devices therein, means whereby the carrying member may be rotated to bring said tools and attaching devices in line with the rotary member, means for locking said carrying member in such positions, and means for connecting said rod with said tools and attaching devices.

8. An apparatus of the class described comprising a hull, a rotary member mounted in said hull and movable inwardly and outwardly therethrough, a carrying member mounted in the hull adjacent to said rotary member, means within the hull whereby said carrying member may be rotated, the carrying member being provided with means for supporting tools and attaching devices therein, means for connecting said tools and attaching devices with said rotary member, and means for locking said tools against rotation in said rotary member.
9. An apparatus of the class described, comprising a hull, a rotary member mounted in said hull and movable inwardly and outwardly therethrough, a carrying member mounted in the hull adjacent to said rotary member, means within the hull whereby said carrying member may be rotated, the carrying member being provided with means for supporting tools and attaching devices therein, means for connecting said tools and attaching devices with said rotary member, 25 means for locking said tools against rotation in said rotary member, and means for locking the carrying member in different positions of adjustment.
10. An apparatus of the class described, comprising a hull, a rotary member mounted in said hull and movable inwardly and outwardly therethrough, a carrying member mounted in the hull adjacent to said rotary member, means within the hull whereby said carrying member may be rotated, and said carrying member being provided with a plurality of apertures adapted to support tools and attaching devices therein.
11. An apparatus of the class described, comprising a hull, a rotary member mounted in said hull and movable inwardly and outwardly therethrough, a carrying member mounted in the hull adjacent to said rotary member, means within the hull whereby said carrying member may be rotated, the carrying member being provided with a plurality of apertures adapted to support tools and attaching devices therein.
12. An apparatus of the class described, comprising a hull, a rotary member mounted in said hull and movable inwardly and outwardly therethrough, a workpiece carrying member mounted in the hull adjacent to said rotary member and comprising inner and outer disks having a plurality of correspondingly spaced apertures, and means within the hull whereby said carrying member may be rotated to bring the apertures therein in line with said rotary member.
13. In an apparatus of the class described, comprising a hull, a rotary member mounted in said hull and movable inwardly and outwardly therethrough, the combination with a carrying member mounted in the hull adjacent to said rotary member and comprising two parallel disks having a plurality of equally spaced apertures, of a plurality of tools and attaching devices the shanks of which are provided with enlarged flanged portions adapted to be passed through the apertures in said disks and serve to retain said tools and attaching devices in connection with said carrying member.
- In testimony that I claim the foregoing as my invention I have signed my name in presence of the subscribing witnesses this 20th day of April 1918.

KARL A. OLSON.
